APPARATUS FOR HEAT TRANSFER BY
CIRCULATING WATERJohn Van Vulp, Chicago, Ill., assignor to Vapor
Car Heating Company, Inc., Chicago, Ill., a cor-
poration of New York

Application March 2, 1940, Serial No. 321,848

2 Claims. (Cl. 237—8)

This invention relates to certain new and useful improvements in apparatus for heat-transfer by means of circulating water, and more specifically to a means for maintaining desired temperature conditions within a space or series of spaces by circulating either hot or cold water through suitable radiators or heat transfer devices in these spaces, together with temperature responsive mechanism for controlling the circulation and temperature of the water or other liquid. This apparatus is specifically designed for heating or cooling the compartments or roomettes of a railway passenger car, although it will be obvious that the apparatus could be used for maintaining desired temperatures in other spaces.

Briefly described, the system or apparatus comprises a tank suitably supported, usually adjacent or beneath the floor of the car, for containing the supply of water or other suitable heat-transfer liquid. Means are provided for heating this water to a desired temperature and keeping it at this temperature, and preferably steam supplied from the pipe running longitudinally of the train from the locomotive is used for this purpose. Other means may be provided for cooling the water supply during the summer season, or whenever and whenever refrigeration is required. A blowing means is provided for forcing air through an overhead conduit or conduits in contact with a radiator heat transfer device positioned in the conduit, and thence through discharge outlets into the several compartments. This radiator is included in a pipe loop extending from and back to the tank, this circuit also including a continuously operating pump for maintaining a circulation of the liquid through the loop. A by-pass valve is also provided for shunting the liquid flow from the supply to the return pipe of the loop without reaching or passing through the radiator at such times as the desired air-temperature has been established in the conduit. This by-pass valve is thermostatically controlled to maintain a selected air temperature. A second pipe-loop extends from the tank through a plurality of the compartments, in series, and thence back to the tank. A pump in this last mentioned loop maintains the circulation at all times that any one of the compartments requires heat. There is a radiator in each compartment that is connected in shunt across a section of the loop-pipe so that a portion of the liquid flows through the radiator if a cutout valve at the radiator is open. This valve is either manually or thermostatically controlled within the compartment to maintain a selected temperature in accordance with the

wishes of the occupants of that particular compartment.

The principal object of this invention is to provide an improved heat-transfer apparatus of the type briefly described hereinabove and disclosed more in detail in the specifications which follow.

Another object is to provide improved means for maintaining the water in the supply tank at the necessary temperature for either heating or cooling, as the requirements may necessitate.

Another object is to provide improved means for automatically controlling the temperature of the overhead air stream.

Another object is to provide improved means for controlling the circulation of the heated water through the floor radiators.

Other objects and advantages of this invention will be more apparent from the following detailed description of certain approved forms of apparatus constructed, assembled and operating according to the principles of this invention.

In the accompanying drawings:

Fig. 1 is a diagrammatic perspective showing the assembled apparatus in a car partially indicated in outline.

Fig. 2 is an elevation, partially broken away, showing a portion of one of the water-circulating loops, and one of the compartment floor radiators and the supply and return connections between the loop and radiator.

Fig. 3 is an elevation of the main temperature selector switch for the overhead heat.

Fig. 4 is a chart illustrating the operation of this control switch.

Fig. 5 is a wiring diagram showing the electrical controls for the complete system.

Referring first to Fig. 1, at 18 and 14 are indicated in broken lines the end walls of one of the compartments or "roomettes" into which the railway car is divided. In the present example, there are two rows of these roomettes, one at either side of the central aisle, although it will be understood that the car might comprise a single row of compartments opening onto a side aisle. In fact, this invention, as to most of its features, is adapted for controlling the temperature in any series of separated spaces, whether in a car or other structure, fixed or movable. It will be understood that in actual practice the car will be much longer and there will be a great many more roomettes than are here shown, a considerable portion of the car being broken away and the grouping of the apparatus condensed in order to show elements of sufficient size within the limited length of the drawings.

In the lower portion of each roomette, adjacent the floor and one side wall thereof, is positioned a heating radiator A which will be hereinafter described more in detail, as well as the connections for supplying hot water thereto. At some convenient location within the compartment or roomette is a switch B for manually selecting the temperature to be maintained by radiator A, and also within the compartment is a thermostat C for automatically controlling the radiator to maintain the desired temperature.

An overhead duct or conduit 15 is provided with at least one outlet 16 leading into the roomette through which tempered air (that is, either heated or cooled air) is discharged into the enclosed space. In the present example there are two of these ducts 15 and 15' extending longitudinally of the car in each upper side portion thereof, the two ducts being connected at one end by a duct 17 in which are positioned a pair of similar radiators or heat-exchangers 18 and 19. A blower or fan D positioned in an air-feed chamber or duct 20 draws air from within the car or from outside the car, or both, and forces this air in contact with the radiators 18 and 19 and thence through the ducts 15 and 15' from which the air is discharged through outlets 16 into the several compartments. The radiators 18 and 19 are supplied with properly heated or cooled liquid in the manner hereinafter described.

Supported at a suitable location on the car, usually adjacent or beneath the floor, and about midway the length of the car, is a supply tank E which holds that portion of the water supply not in circulation through the pipe systems, radiators, and heating and cooling mechanisms hereinafter referred to. While the liquid used is herein referred to and claimed as "water," it will be understood that other suitable liquids could be used, and the water will usually contain a suitable amount of anti-freeze solution so that no portion of the system will freeze up in cold weather.

While the water in the supply tank E and circulating systems may be heated in any suitable manner, an approved apparatus is herein disclosed whereby steam is used, obtained from the main steam pipe 21, which extends as usual from the locomotive, or other suitable source of supply, throughout the length of the train. Steam flows from this main 21 through pipe 22 to the vapor regulator, indicated at 23. This vapor regulator, which is well known in the art, contains a valve which permits the flow of steam through pipe 24 and distributing valve 25 until steam returns to the regulator through pipe 26, whereupon the valve in the regulator is closed. When the electrically controlled distributing valve 25 is in "closed" or off position, the steam flow will be directed from pipe 24 through valve 25 and pipe 26 back to the vapor regulator. When valve 25 is in open position, the steam will flow through pipe 27 to and through the heat-exchanger, indicated generally at 28, and thence through pipe 29 back to the valve 25 and through pipe 26 to the vapor regulator. The heat-exchanger 28 is formed with a plurality of adjacent annular chambers or passages through one set of which this steam flows, and through another set of passages water from tank E flows so as to be heated by the condensing steam. This water flow is from tank E through pipe 30, T-fitting 31 and pipe 32 into one end of the connected water passages in the heat-exchanger 28, thence from the heat-exchanger through pipe 33, T 34 and 75

pipe 35 into the other end of tank E. A pair of manually operated cut-off valves 36 are located in the pipes 32 and 33, these valves being open when the heating system is in operation, but closed when the cooling system, hereinafter described, is used. At 37 is indicated an aquastat of well known form, comprising a thermostatic responsive to temperature changes of the liquid in the tank E and adapted to open and close the valve 25 so that the water in tank E will be maintained at a predetermined temperature. The electrical connections between aquastat 37 and valve 25, as well as all other electrical connections, are indicated in the wiring diagram of Fig. 5, hereinafter described.

At F is indicated a suitable refrigerating apparatus, for example, an ice-water sump or a mechanical refrigerating unit. One end of this refrigerating unit F is connected through pipe 38 with the T-fitting 31, and the other end is connected through pipe 39 with the T-fitting 34, and cut-off valves 40 are located in the respective pipes 38 and 39. When the heating system is in operation valves 40 will be closed, but during the refrigerating season, valves 40 will be open and a pump G in pipe 39 will be continuously operated to maintain a circulation of the liquid from tank E through the refrigerating device F thereby suitably cooling the water supply.

The circulation pipe-loop for supplying tempered liquid from tank E to the overhead radiators 18 and 18 comprises a pipe 41 extending from the tank E, a booster pump H, pipe 42, by-pass valve J and pipe 43 to one end of the radiator or radiators 18 and 19, thence back through pipe 44, one-way valve 45 and pipe 46 to the tank E. The pump H is continuously operating (when either the overhead heating or cooling systems are in operation), and when the by-pass valve J is in its open or "on" position the liquid flow will pass continuously to and through the radiators 18 and 19 through the system already described. However, when the valve J is in its closed or "off" position, the circulating liquid will be shunted through pipe 47 from valve J directly back to pipe 46 and thence back to the tank E. The one-way valve 45 prevents flow in the opposition direction through pipe 46. It is simpler and more economical to let the pump H run continuously than it is to stop and start this pump at frequent intervals, and the apparatus just described serves to shorten the effective length of the loop by opening and closing the valve J so that the supply of heated or cooled liquid to the radiators 18 and 19 will be turned on or off as desired. At K is indicated diagrammatically a grouping of suitable thermostats in one of the air-conduits 15 which cooperate with suitable selecting means located in or on the panel indicated diagrammatically at L for controlling the by-pass valve J. It will be understood that this panel L contains most of the relays and switches hereinafter shown and described in connection with Figs. 3 and 5, and this panel may be located at any suitable position in the car.

Hot water is supplied to the "floor heat" radiating system through the outlet pipe 48 near one end of tank E, thence through pipe 49 and T-fitting 50 through either or both of a pair of similar pipe loops M and N, thence through pipe 51, pump O and pipe 52, back to the tank E. The loop M comprises pipes 53, 54, 55, 56, balancing valve 57, and pipe 58 which leads into the pipe 51, already described. The other loop N may

be in all respects the same as loop M and comprises the pipes 53' to 58', respectively. It will be understood that when the tank E is located substantially midway the length of the car, it is convenient to use two separate loops, such as M and N. Otherwise a single loop could be used.

The several radiators A are each provided with an individual inlet valve P and are shunted across portions of one or the other of the loops M and N in the manner hereinafter described so that when any valve P is open, a portion of the circulating fluid will pass through the associated radiator A. As will be hereinafter shown in connection with Fig. 5, whenever any one of the valves P is open, the pump O will operate so as to maintain a circulation of hot water through the supply loop or loops, but when all of the valves P are closed, the pump O will cease operating. The valves 51 and 51' are so adjusted as to balance the system, that is, so that the liquid flow will divide equally between the two loops M and N.

An air-cushion compression tank 59 is connected at 60 into the water circulation system. It will be understood that this tank contains an adequate volume of air which will be compressed by variations in the water pressure so as to provide a substantially constant and suitable pressure throughout the circulating system. Tank 59 may be provided with a suitable relief valve and air vent, indicated at 61.

Referring now more particularly to Fig. 2, it will be noted that each floor-radiator A comprises (in the present example) a pipe section 62 fitted with a plurality of radiating fins 63 to increase the heat-transfer surface. A supply riser 64 extends upwardly from the pipe fitting 65 interposed in the main loop pipe 53 to the inlet valve P which communicates with one end of the radiator A. The other end of the radiator is connected by a return riser 66 with another fitting 67 interposed in pipe 53.

The solenoid valve P comprises a movable valve member 68 carried at the lower end of valve stem 69 and normally held down in closed position against valve seat 70 by the spring 71. When the solenoid 72 is energized it will pull up the valve member against the resistance of the spring so as to open the valve passage leading to the radiator. The valve may also be moved to open position when desired, in case of failure of the electrical operating connections, by means of the cam 73 carried at the inner end of manually operable shaft 74 and engaging under the collar 75 on the movable valve member. The solenoid 72 is automatically operated to maintain a selected temperature in the roomette by means of the electrical connections hereinafter described in connection with Fig. 5.

A baffle member 76 fitted within the pipe-fitting 65 is provided with an inlet opening 77 of less diameter than that of pipe 63 so that a portion of the heated water stream will flow through opening 77 and continue through loop-pipe 53 while another portion of the heated water will be deflected upwardly through pipe 64 and thence to radiator A, all as indicated by the arrows in Fig. 2. Obviously this can only occur when valve P is open. At other times the only flow that can continue is that which proceeds outwardly through pipe 53, as shown by the lower arrow, at the lower left hand side of Fig. 2. The internal fitting 78 at the other end of the radiator and within fitting 67 is preferably reversed so that its outlet 79 is adjacent the top of pipe 53. This

will cause the hotter water which flows onward through pipe 53 to flow out along the upper portion of the loop beyond the radiator, whereas the partially cooled water returned through riser 66 from radiator A will flow into the lower portion of the pipe loop. The baffle connections within fittings 65 and 67 are of well-known type and well suited for this purpose, but it will be understood that other types of dams or baffle members could be used so as to shunt any desired portion of the water stream through the radiator A.

The electrical control system will now be described, referring more particularly to Figs. 3, 4 and 5 of the drawings. The main control switch R (Fig. 3) is preferably mounted in or on the panel L and comprises a casing 80 within which is mounted a plurality of switches 1 to 12 inclusive which are shown at various locations in the wiring diagram of Fig. 5. These several switches are successively closed or opened, singly or in groups, by movement of the operating handle 81 on the face of casing 80, which handle is movable to seven different selective positions including one "off" position, three heating positions and three cooling positions, all as indicated on the dial in Fig. 3. In the chart of Fig. 4, these several positions are indicated in the first vertical column, in horizontal alignment with which are twelve columns corresponding to the switches 1 to 12 inclusive. In each of these vertical columns where a dot appears, this indicates that the corresponding switch is closed. For example, in the "heating high" position of the switch, the individual switches 1, 9, 10, 11 and 12 are closed, whereas switches 1 to 6 inclusive and 8 are open. In the "cooling low" position, switches 1, 2, 8 and 10 are closed and all others are open. This switch R controls the selection of temperatures for the "overhead heat" or circulated air for both heating and cooling. The floor heat by means of radiator A is controlled by the individual switches B in the several compartments, as hereinafter described.

Referring now more particularly to Fig. 5, in the lower left hand portion of this figure is indicated a fan-switch S, which is preferably located in the panel L, and which controls the fan or blower hereinabove referred to and indicated at D in Fig. 1. The motor for this blower is also indicated by the reference character D in Fig. 5. This fan-switch S comprises a pair of simultaneously movable arms or contacts 82 and 83, the arm 82 being movable into engagement with either of a pair of fixed contacts 84 and 85 so as to change the amount of selected resistance in the fan-motor circuit and thereby provide two fan speeds. The circuit extends in an obvious manner from negative power main 86 through switch S and fan-motor D to the positive main 87. At the same time the other arm 83 of switch S will be engaged with one or the other of the contacts 88, thereby completing a circuit connection from the negative power main 86 to the negative power main 89 and making operable, as will be hereinafter apparent, the various controlling circuits for the overhead heating and cooling mechanism. In other words, none of these overhead controls are operative until the fan-switch S has been closed. This prevents circulation of hot or cold water through the overhead radiators 18 and 19 unless the fan D is operating so as to blow air over these radiators.

In the upper portion of Fig. 5 are shown two substantially identical groups of electrical elements and circuits, bracketed as X and X', re-

spectively. The similar elements in each group are indicated by identical reference characters. Each group represents the electrical control circuits and elements for one roomette or compartment of the car and although only two of these groups are shown in the drawings, it will be understood that there is a similar group of circuits for each of the several roomettes. A description of one group will suffice for all. Referring for the moment to Fig. 4, it will be noted that switches 11 and 12 of the main control switch R are closed whenever this main switch is turned to any one of the three over-head heat positions or to the "off" position. However, these two switches are open when the main switch R is in any one of the three cooling positions. These switches 11 and 12 (as shown in the upper portion of Fig. 5) are associated with the "floor-heat" system and it will thus be seen that the floor-heat radiators A are operative at any time except when the cooling system is operating. It will be seen that when switch 11 is closed it will complete a circuit from negative main 90 to positive main 91 so as to energize the relay coil T. When relay T is energized, it serves to close each of the three movable contacts t, t' and t'' against the pairs of fixed contacts positioned adjacent thereto. When relay T is de-energized, the several movable contacts t, t' and t'' will be raised to the position indicated in the drawings so as to break the circuits which they control. When a certain predetermined temperature is reached within the compartment, the mercury-tube thermostat C is adapted to complete a circuit through wire 92, the mercury column of the thermostat, and wire 93 so as to short-circuit the coil of relay T. Whenever the compartment temperature falls below this predetermined temperature, the mercury will fall so as to break this shunt circuit and the relay T will immediately be energized. A heating coil 94 is closely associated with the thermostat C, this coil being energized through a circuit extending from negative main 90 through wires 92, 95, heating coil 94, wire 96, a portion of resistance 97 of the controlling switch B, wire 98, fixed resistances 99 and 100 and thence to the positive main 91. The amount of additional heat imparted by coil 94 will determine the temperature at which the thermostat C will function to de-energize the relay T. For example, if the thermostat C is so designed as to function to close the shunt circuit therethrough at a room temperature of 75°, if 5° of additional heat are imparted to the thermostat by the coil 94, then the thermostat will actually function at a room temperature of 70°. It will now be apparent that if the selector switch B is adjusted to add to or subtract from the amount of resistance 97 that is effective in the circuit, there will be a consequent adjustment of the heating current in coil 94 and the exact temperature at which the thermostat will function will thus be selected. The dial on switch B may be so calibrated as to indicate the room temperature that is selected.

Whenever the roomette temperature falls below the desired temperature, the shunt circuit through the thermostat will be broken and relay T will be energized so as to close the three movable contacts t, t' and t''. The contact t'' completes a circuit through the water-circulating pump O, which circuit, it will be noted, has already been completed through the switch 12 of main control switch R. The contact t' completes a circuit through the solenoid winding 72

of valve P (Fig. 2) so that the hot water will be permitted to flow through radiator A. The contact t completes a short circuit around the resistance 100 so that this amount of resistance 100 will be temporarily cut out of the heating circuit for heater 94. As a consequence a slightly greater amount of heat will be added to the thermostat C so as to anticipate or advance the temperature at which the supply of heating medium to radiator A will be cut off. In other words, if a temperature of 72° is desired in the roomette, the flow of hot water to the radiator may be cut off at 71° since there is a lag in the heat transfer from radiator A to the air of the room and the heat already in the radiator will be added to the room temperature after the valve P is closed. As soon as the shunt circuit through thermostat C has been completed, relay T will be de-energized and all of the contacts t, t' and t'' will be opened. Breaking the heating circuit at t will again add the resistance 100 to the heating circuit so as to reduce the auxiliary heat imparted by coil 94 and permit the thermostat C to again respond directly to the room temperature as selected by switch B. Breaking the solenoid switch at contact t' will de-energize the solenoid 72 and permit valve P to close. Breaking the pump circuit at t'' would apparently stop the pump O, but it will be noted that in each set of roomette controls there is a similar contact t'' and all of these switches are connected in parallel with one another by the wires 101 and 102 so that in the event that any one of the roomettes is calling for heat, that is the valve P is open and water may flow through the radiator A, then the pump circuit will remain closed and the pump O will continue to operate. In the event that the temperature requirements are, for the time being, satisfied in all of the roomettes or compartments, then all of the contacts t'' will be opened and the pump O will cease to operate.

The overhead-heat controls will now be described, referring more particularly to the central portion of Fig. 5. First it will be noted that (Fig. 4) when the main control switch R is moved to any one of the heating positions "high", "medium" or "low" the switches 7, 9 and 10 will all be closed. The closing of switch 10 will complete a circuit from negative main 103 to positive main 104 through the pump H which will run continuously as long as the overhead-heat system is in operation. The closing of switch 9 will complete a circuit through the relay U between mains 89 and 81, this relay controlling the by-pass valve J. The relay U includes a movable contact u which alternatively completes one or the other of two branches of a circuit that has been completed by the closing of switch 7. The thermostat 105 (which may be similar to the thermostat C already described) is adapted to complete, at a predetermined temperature, a shunt circuit through wires 106 and 107 about the relay U so as to de-energize this relay. Assuming that the thermostat 105 is adapted to complete this shunt circuit at a "high" temperature of 76°, and also assuming that the roomette temperature has fallen below this point, then the shunt circuit will be broken and relay U will be energized. This will draw down the bridging contact u so as to connect the fixed contacts 108 and 109 and a circuit will be completed from negative main 110 through movable contact 111, solenoid coil 112, wires 113 and 114, relay contacts 108, u and 109, and thence through closed switch 7 to the positive main 115.

The solenoid 112 is a part of the operating mechanism for by-pass valve J and, when energized, serves to move this valve so that the heated water will flow on through the overhead radiators 18 and 19 before returning to the supply tank E. At the completion of this valve operating movement, the movable contact member 111 will be moved up out of engagement with fixed contact 116 into engagement with another contact 117, as indicated in dotted lines. Another solenoid 118 of the by-pass valve J is adapted to move the valve back to a position whereby the hot water will be by-passed through pipe 47 and will not reach the radiators 18 and 19. When the desired temperature has been reached within the roomette and a shunt circuit has been completed through thermostat 105, the relay U will be de-energized so that contact u will move back into engagement with a pair of fixed contacts 119 and 120, and it will be now apparent that another circuit will now be completed through solenoid 118 so as to operate the by-pass valve to the "off" position. At the completion of this movement the switch arm 111 will be moved back to the original position shown in solid lines. The switch operating solenoids 112 and 118 require a rather heavy current, and if this current was permitted to flow for a protracted time the coils might be burned out. For this reason a thermally operated safety switch is indicated at 121 which will break this circuit in the event that the valve or operating mechanism sticks and the current flows too long. In this event a pilot light, indicated at 122, will throw additional resistance in the circuit and will give a warning signal.

The relay indicated at W is normally energized through its circuit extending between the mains 119 and 116. A shunt circuit extending about relay W and adapted to de-energize the same may be completed through a switch 37' which is actuated by the aquastat 37 (Fig. 1) responsive to the temperature of the water supply in tank E. The distributing valve 25 (Fig. 1) which controls the steam flow through heat exchanger 28, is of well known type and comprises a pair of operating solenoids 123 and 124 adapted to move this valve to the "off" and "on" positions, respectively. The relay W comprises a movable bridging contact w which, when the relay is de-energized, will be in the upper position now shown in the drawings so as to complete the "off" circuit through solenoid 123. When relay W is energized the contact w will be moved down so as to complete the "on" circuit through the other solenoid 124. The operation of this portion of the mechanism is much the same as that of the by-pass valve J, already described.

A heating coil 125 is associated with thermostat 105 so as to lower the temperature at which the thermostat will function, this coil 125 being energized through a circuit having two branches, one of which includes the resistance 126 and switch 5 and the other of which includes a resistance 127 and switch 6. It will be noted that if the main control switch R is moved to the "heating low" position, then the switch 5 will be closed. This will result in a certain amount of heat being added to thermostat 105 in addition to that imparted by the room, so that the overhead-heat will be turned off at a lower temperature. If main switch R is moved to the "heating medium" position the switch 6 will be closed instead of the switch 5. This will place a resistance 127, of different size, in the circuit so

that the system will function at a medium temperature.

Referring now to Figs. 3 and 4 in connection with the lower portion of Fig. 5, it will be noted that when main control switch R is moved to any one of the three cooling positions the switches 1, 8 and 10 will be closed. Switch 10, as already noted, serves to close the energizing circuit for pump H which operates the same for either heating or cooling. The closing of switch 1 serves to complete a circuit between mains 89 and 87 through the cooling pilot relay 128 and this relay closes the switch 129 completing an energizing circuit through the relay Y. The energization of relay Y serves to close a contact y which completes an energizing circuit between mains 86 and 87 for energizing the cold water circulating pump G (see also Fig. 1). The closing of switch 1 also completes an energizing circuit between mains 89 and 87 for the relay Z. This relay Z is adapted to control the bypass valve J during the cooling operations. The three thermostats 130, 131 and 132 are positioned in shunt circuits extending around relay Z, these circuits being controlled respectively by the three switches 2, 3 and 4. It will be noted from Fig. 4 that when the main switch R is moved to the "cooling low" position, the switch 2 will be closed so that when thermostat 130 responds to a certain predetermined temperature within the roomette a shunt circuit will be completed, de-energizing the relay Z. In a similar manner the switch 3 will be closed at a certain medium temperature to complete a circuit through relay 131 which functions at this medium temperature. Similarly switch 4 will be closed at the "cooling high" temperature so that thermostat 132 will be in control of the relay. The contacts 133 and 134 are adapted to be bridged in any suitable manner for testing purposes when the main switch is in the "cooling high" position. When relay Z is de-energized, the movable contact z (see central portion of Fig. 5) will be in the upper position now shown so as to complete a circuit through the operating solenoid 112 of the by-pass switch J and move this switch to the "on" position. When the relay Z is energized, the contact z will be moved down so as to complete an energizing circuit for solenoid 118 and move the switch to the "off" position. It will be noted that the switch 8 is in both of these circuits and will be closed, as already noted, when the main selector switch R is in any of the cooling positions. It will be noted that the by-pass valve J is operated in the same manner as for heating with the exception that the movements are reversed. Obviously, when a certain high temperature is reached within the roomette it will be desirable to turn the heat off during the heating season, but during the cooling season the cooling apparatus is turned on when a certain maximum temperature is reached. Many of the wires and resistances shown in Fig. 5 have not been specifically referred to, but it is believed that their purpose will be obvious. Many variations might be made in the wiring system hereinabove shown and described, the one here disclosed by way of example being suitable for the purpose.

It will be noted that no overhead heating or cooling is possible unless the fan D is operating, since the switch S must be closed in order to complete a circuit through the negative main 89 from which power is obtained for all of the cooling control circuits, and also for the controlling relay U of the overhead heating circuits. However, if

the switch R is moved to the "off" position so that neither the overhead heating or the overhead cooling is operable, the switch S can still be closed to cause the fan to operate for ventilating purposes. The "floor" heat obtained from radiators A can be operated even though the fan switch S is open and the fan is not in operation since the roomette circuits for controlling the floor heat are energized from power mains 90 and 91 which are in no way controlled by the fan switch. However, the main control switch R must not be in any of the "cooling" positions or the floor-heat will not be operable since at this time the switches 11 and 12 will be open and the circuit for energizing the main controlling relay T, and for energizing the pump O cannot be completed.

I claim:

1. In a means for heating a plurality of compartments by means of hot water, a supply tank, means for maintaining the water in the tank at a predetermined temperature, a pipe loop leading from the tank through the several compartments in series and back to the tank, a motor-driven pump in said loop for enforcing a circulation of heated water through the loop and tank, a plurality of radiators one in each compartment, a pair of riser pipes for each radiator connecting the respective ends of the radiator with the pipe loop at spaced apart locations, a plurality of cut-off valves one for each radiator and located in one of said pair of risers, means in said pipe connections for causing a portion of the circulating

liquid stream to be shunted through a radiator when its respective valve is open, means for individually opening and closing the valves, and means for causing the pump to operate when any one of the valves is open but stopping the pump when all valves are closed.

2. In a means for heating a plurality of compartments by means of hot water, a supply tank, means for maintaining the water in the tank at a predetermined temperature, a pipe loop leading from the tank through the several compartments in series and back to the tank, a motor-driven pump in said loop for enforcing a circulation of heated water through the loop and tank, a plurality of radiators one in each compartment, a pair of riser pipes for each radiator connecting the respective ends of the radiator with the pipe loop at spaced apart locations, a plurality of cut-off valves one for each radiator and located in one of said pair of risers, means in said pipe connections for causing a portion of the circulating liquid stream to be shunted through a radiator when its respective valve is open, electrically actuated, thermostatically controlled means in each compartment for opening and closing the radiator valve to maintain a selected temperature in the compartment, said electrically actuated means serving to cause the pump to operate when any valve is open but stopping the pump when all valves are closed.

JOHN VAN VULPEN.
